UNITED STATES PATENT OFFICE

2,543,654

SHIP'S BOW CONSTRUCTION

Oscar J. Baggerud, Jersey City, N. J.

Application March 28, 1947, Serial No. 737,877

1 Claim. (Cl. 114—79)

1

This invention relates to the manufacture of a ship's bow as applied to an existing ship, and my primary object is to reduce the cost of such manufacture as compared with the cost of fitting in a new bow as hitherto made by cutting off the bow of the ship and replacing it with a new one of longer length in order to increase the speed of the ship.

A second object of my invention is to obtain additional safety in the ship by the addition of the new bow.

A third object of my invention is to provide a bow of a "soft" construction so as to minimize the danger of a collision without endangering the safety of the ship.

According to the present invention the ship's bow is left intact and a new separate bow is made up and welded or riveted to the fore part of the ship. Thus the new bow, which may be termed a false or dummy bow, will form a second skin the length of this bow. The skin of the original bow-part of the ship will then serve as a collision bulkhead, thus increasing the safety of the ship. The structure and shell plating of the new bow can be lighter than are required in a ship or a new bow of the ordinary construction.

The gain in speed may not, in many cases, be worth the expenditure required for the ordinary bow construction, while with the present invention advantage can be taken of the increase in speed afforded by a better designed bow. Furthermore the additional cubic capacity gained in an ordinary bow construction can not be fully utilized for a heavy load, consequently the false bow is no disadvantage in this respect.

The invention is illustrated in the accompanying drawing forming a part of this specification, where

Figure 1 is an elevation of the bow, attached to the ship, looking to port.

Figure 2 is a plan view of the bow and part of the ship.

Figure 3 is an enlarged view showing details of construction.

In Figure 1 the numeral 1 indicates the stem of the ship in its original form, 2 indicates the stem or bent plate in the new bow, 3 is the baseline of the ship and 4 and 5 are the second and upper deck lines respectively. The shell plating 6 is shown with horizontal welding or riveting seams 7, but may be arranged in any fashion. Vertical seams are not shown. The aft end of the new bowplating is welded or riveted to the shell of the ship, port and starboard, as shown by line 8 on the starboard side. The bow may be

2

built up in the yard and then transferred and fitted to the ship. In order to be able to weld the structure to the ship in the narrow space between the two skins, it will be necessary to leave off sections of the plating 9. It will then be possible for a man to gain access between the frames 10 for welding. While frames are required throughout the length of the bow as in any ship, these are shown in the opening of the removed plate sections 9 only, and in one dotted line extending the height of the bow, in order not to complicate the drawing.

Figure 2 shows the top contour of the for'd part of the ship and of the new bow. Line 12 is the centerline of the ship.

Figure 3 shows the frames 10, which may be angles or any other sectional shape, and members 11, which may be bars, plates, profilirons, or built up shapes welded or riveted to the frames and shell of the ship. 12 is the centerline of the ship. Decks may be extended into the new bow space and this space inside may be utilized in any suitable manner desired. Reinforcement construction may be applied in any suitable manner desired.

The shape of the bow is not restricted to any definite form, but may be of any design, and various changes in the internal construction of the bow may be resorted to without departing from the spirit of my invention or the scope of the subjoined claim:

Having thus described my invention I claim:

In remodeling the hull of an existing ship having a sea-contacting bow provided with a keel, a stem, external shell plating and internal frames; the improvement which consists in permanently and immovably securing to such an original complete bow, externally of the latter, a forwardly extending added fore part enclosing such original bow from keel to deck and constituting an integral part of the remodeled hull, said added fore part having its own deck, stem, internal bracing and external shell plating merging with the shell plating of the original hull at the point of tangency between them and forming watertight joints therewith, whereby the thus added fore part becomes an inherent component permanent part of the remodeled hull, the shell plating on such added fore part extending rearwardly from said second named stem on both sides of said hull and terminating in edges that engage said hull, said shell plating having spaced openings therein adjacent said edges affording access to the bracing and shell plating; securing said internal bracing to said first-named external shell

plating adjacent said access openings and within the second-mentioned shell plating, and securing plating sections over said access openings.

OSCAR J. BAGGERUD.
